Primary Examiner — Eric L Goodman*Assistant Examiner* — Anessa Martinez(74) *Attorney, Agent, or Firm* — CALDERON SAFRAN & WRIGHT P.C.(57) **CLAIM**

The ornamental design for a vehicle headlight, as shown and described.

DESCRIPTION

FIG. 1 is a front view of a vehicle headlight showing my new design;
 FIG. 2 is a front upper right perspective view thereof;

FIG. 3 is a left perspective view thereof;

FIG. 4 is a right side view thereof;

FIG. 5 is a rear view thereof;

FIG. 6 is a rear left perspective view thereof;

FIG. 7 is a top view thereof; and,

FIG. 8 is a bottom view thereof.

The broken lines in the drawings depict portions of the vehicle headlight that form no part of the claimed design.

1 Claim, 8 Drawing Sheets(56)
